UNITED STATES PATENT OFFICE.

JAMES T. FREEMAN, OF WOBURN, MASSACHUSETTS.

FRAME FOR LEATHER-WORKING MACHINES.

SPECIFICATION forming part of Letters Patent No. 340,712, dated April 27, 1886.

Application filed January 23, 1886. Serial No. 189,437. (No model.)

To all whom it may concern:

Be it known that I, JAMES T. FREEMAN, of Woburn, county of Middlesex, and State of Massachusetts, have invented certain new and useful Improvements in Frames for Leather Machinery and the Like, of which the following is a full, clear, concise, and exact description, reference being had to the drawings accompanying and forming a part hereof, in which—

10 Figure 1 is a side elevation, and Fig. 2 is a plan view, of my improved frame as adapted for glassing-jacks.

Certain machinery used in the manufacture of leather—such, for example, as glassing and pebbling jacks—are provided with frames which are commonly constructed of wood, and since the upper part, which carries the head, requires to be rigid and to maintain its position with great exactness relatively to the bed or table on which the leather is placed, these wooden frames require to be heavy and are consequently clumsy in construction, and they require to be stayed up to the ceiling and practically built into the room in which the machine is designed to operate, and are with difficulty arranged so as to maintain the necessary rigidity.

The object of my present invention is to provide a frame for such machines which will be self-contained, and the various parts of which will be perfectly rigid, or substantially so, with relation to the other parts; and it consists in a frame provided with a curved brace arranged in the peculiar manner shown and hereinafter described.

15 A is the upper projecting arm of a glassing-jack frame, and B is the lower portion, which supports the bed. These parts are connected with a ribbed body, the ribs being placed on the body wherever most convenient and efficient, according to the form of the body, in view of the moving parts as pulleys, shafts, &c., to which it must be adapted, and the web

portions being cut away to lighten the frame wherever it is deemed desirable. On the upper part of the frame of the body, at or near the base of the projecting arm A, which it is desired to render rigid, an arm, D, is extended upward, and from the projecting arm A, over the top of the projection D, and extending downwardly and rearwardly to the base E of the frame, is an upwardly-curved brace, F. This brace may be divided, as is the case in the glassing-jack frame shown in the drawings, to make room for a pulley or other part; but it must be rigid—that is, cast in one piece—or its parts must be rigidly secured together, and it must be integral with or rigidly secured to the base of the frame, as at a, and to the upwardly-projecting arm D, as at d, and to the projecting arm A, as at f. In the frame shown this brace is cast with the frame and a stay, h, which forms one side of the pulley-opening, is bolted rigidly to it for convenience in construction.

20 By the use of the curved brace F, which is the chief feature of my invention, secured firmly to the rear of the base, and at its other end well out on the projecting arm A, which it is desired to render rigid, and intermediately to the projection D of the frame, a rigid frame, comparatively light and inexpensive, is obtained, and which can be set up easily and inexpensively and is ready for immediate use as soon as placed in position.

25 What I claim is—

A leather-dressing machine having a projecting arm and an upwardly-curved brace integral with said arm and supporting it at its outer end, said brace extending rearwardly to the base of the machine, substantially as set forth.

30 JAMES T. FREEMAN.
